AUTOMATIC TOOTHBRUSH BOX

Abraham Brody, New York, N. Y.

Application October 31, 1938, Serial No. 237,976

4 Claims. (Cl. 206—15.1)

This invention relates to new and useful improvements in an automatic toothbrush box.

More specifically, the invention proposes the construction of a holder for toothbrushes and tooth paste tubes vertically, slidably engaged within a container in a novel manner to be moved upwards within said container to permit the toothbrushes and tooth paste tubes to be removed therefrom.

10 Another object of this invention is the provision of a cover hingedly mounted on the open end of the container for closing the same when the holder is in its lowered position.

Still further the invention proposes the provision of a link extended between the top end of said holder and the bottom face of said cover in a novel manner so that said cover will be moved to an open position when said holder is raised.

20 Another object of this invention is the provision of a novel means for permitting the holder to be raised by merely pulling a string located at the side or bottom of the container.

Still further the invention proposes the construction of a novel means for holding the string in its extended position in a particular manner for holding the holder in its raised position.

For further comprehension of this invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a front elevational view of an automatic toothbrush box constructed according to this invention.

40 Fig. 2 is a perspective view of the toothbrush box showing the holder in the raised position.

Fig. 3 is a plan view of Fig. 2.

Fig. 4 is a sectional view taken on the line 4—4 of Fig. 3.

45 Fig. 5 is a view similar to Fig. 1 but illustrating a modification of the invention and having a portion thereof broken away to reveal interior construction.

Fig. 6 is a sectional view taken on the line 6—6 of Fig. 5.

50 Fig. 7 is a view looking in the direction of the line 7—7 of Fig. 6.

Fig. 8 is a perspective view of the clip and clamp per se.

55 Fig. 9 is a perspective of another modified form of the device.

The automatic toothbrush box, according to this invention, includes a container 10 constructed of wood or other similar material and having a cover 11 pivotally supported on the upper end thereof for closing the top opening. The back 5 wall of the container 10 is formed with upwardly extending lugs 10^a and the back edge of the cover 11 is formed with cutouts 11^a into which the lugs 10^a extend for permitting pins to be extended therethrough for pivotally supporting the 10 cover.

The toothbrush box may be supported on a hook or nail, by engaging the same through a hole 10^b formed in a projection 10' mounted on 15 the top edge of the container 10.

A holder 12 in the form of a container for toothbrushes and tooth paste tubes is vertically slidably mounted within the container 10. This holder is formed with a plurality of walls 13 extended across the width thereof for dividing the 20 interior of the holder into a number of compartments 12. The center compartment 12^a is slightly larger than the other compartments for receiving the tooth paste tube, while each of the other container compartments have sufficient 25 space for receiving a toothbrush. The inner face of the cover 11 is divided off to correspond with the number of compartments in the holder 12 and each of the divided off sections of the cover is provided with an identification mark 14 for 30 properly identifying each of the compartments 12^a.

A link 15 has one of its ends pivotally attached to the bottom face of the cover 11 and the other of its ends pivotally attached to the upper end of 35 the holder 12 for moving the cover 14 to an open position when the holder 12 is raised within the container 10. This link 15 also serves to move the cover 11 back to its closed position when the holder 12 moves downwards within the container 40 10.

A means is provided for lifting the holder 12 within the container 10 to align the top edge of the holder 12 with the top edge of the container 10 as shown in Fig. 2. This means comprises a 45 string 16 having one of its ends attached to the bottom wall 12^b of the holder (see Fig. 4) and the other of its ends extended through an elongated slot 17 formed in the front wall of the holder 12 and through an aligned opening 18 formed in 50 the front wall of the container 10. The outer end of the string 16 is formed with a pull 19 in the form of a flower or other similar object, for permitting the end to be grasped and pulled for raising the holder 12. The slot 17 through which 55

the string 16 passes permits the holder 12 to slide upwards when the string is pulled.

The operation of the device is as follows:

5 The toothbrushes and tooth paste tubes are placed within the compartments 12^a formed within the holder 12. For raising the holder to permit the toothbrushes and tooth paste tubes to be removed therefrom, the string 16 is pulled causing the holder 12 to move upwards to a position in which its top edge will be aligned with the top edge of the container 10. This movement of the holder 12 also causes the cover 11 to be moved to an open position through the medium of the link 15 extended between the cover and the holder 12.

10 After the brushes and paste have been removed therefrom and the string 16 is released, the force of gravity will return the holder 12 to its normal position rested upon the bottom wall of the container 10 which movement automatically causes the cover 11 to be moved back to position in which it will close the open top end of the container 10.

15 According to the modification shown in Figs. 5-8 inclusive the construction of the toothbrush 25 box is similar to that previously described except for the means for lifting the holder within the container 10. This means comprises a string 16' having one of its ends attached to the bottom wall 12^a of the holder 12. An intermediate portion of the string 16' extends upwards and engages over a roller 20 rotatively supported upon a shaft 21. The shaft 21 has its ends extended through elongated slots 22 formed in opposite walls of the holder 12. The outer ends of the 30 shaft 21 are engaged into openings 23 formed in the walls of the container 10. The openings 23 are aligned with the slots 22 formed in the holder 12.

20 The other end of the string 16' extends through an enlarged opening 24 formed in the bottom wall 12^a of the holder 12 and through an arcuate shaped slot 25 formed in the bottom wall of the container 10. The end of the string 16' is formed with a pull 19 in the form of a ball or other similar object. This ball 19 is located at the bottom of the container 10.

25 This form of the invention is also provided with a means for holding the string 16' in its extended position for preventing the holder 12 from moving downwards until so desired. This means comprises a clip 26 for guiding the string 16' and through which the string passes. This clip 26 is located between the adjacent faces of the bottom walls of the holder 12 and the container 10 and is formed at one side with a lever 26^a by which the clip is pivotally supported to move in arc parallel with the arcuate shaped slot 25 formed in the bottom wall of the container 10.

30 A clamp 27 is mounted on the bottom wall of the container 10 at one end of the arcuate shaped slot 25 and is provided with an outwardly extending lug 28 formed with openings 28^a through which fastening elements 29 are engaged for holding the clamp in position at the end of the 35 arcuate slot 25. A cotter pin 30 extends between the ends of the clip 26 for maintaining the string 16' in position within the clip. The ends of the clamp 27 are provided with cutouts 27^a into which the cotter pin 30 extends for permitting the clip 27 to be engaged therein. One side 27^b of the clamp 27 is slightly cut away to permit the lever 26^a of the clip 26 to pass therethrough when the clip 26 is engaged into the clamp 27.

40 The operation of this form of the device is as follows:

45 The string 16' is pulled downwards causing the intermediate portion thereof to roll over the roller 20 and extend the holder 12 within the container 10. For holding the holder in its raised position within the container the string 16' is pulled towards the clamp 27 causing the clip to be engaged therein. The clamp 27 will cause the walls of the clip 26 to be tightly clamped around the string 16' for maintaining it in its extended position. For releasing the string 16' it is merely necessary to pull the same in a direction away from the clamp 27 to free the clip therefrom to permit the force of gravity to return the holder 12 back to its normal position. In other respects this form of the invention is similar to the previous form. 15

50 Ventilation holes 10^c and 12^c are provided at the side of the container 10 and the bottom wall 12^b of holder 12, to permit the circulation of air and dripping of any water or fluid in the device. 20

55 In Fig. 9, a plunger 31 is provided for lifting the holder 12 and cover 11.

60 While I have illustrated and described the preferred embodiments of my invention, it is to be understood that I do not limit myself to the precise constructions herein disclosed and the right is reserved to all changes and modifications coming within the scope of the invention as defined in the appended claims. 25

65 Having thus described my invention, what I claim as new, and desire to secure by United States Letters Patent is:

70 1. An automatic toothbrush box, comprising a container with an open top, a cover hingedly mounted thereon for closing said top, a holder for toothbrushes and tooth paste tubes vertically slidably mounted in said container, a link connecting said holder and cover together for moving the cover open when the holder is lifted, and means for lifting said holder, comprising a string 35 passing through an aperture in said container to the exterior thereof and the inner end of said string being attached to said holder at a point to cause said holder to be lifted when the string is pulled, said string having one of its ends attached to the bottom wall of said container, a roller rotatively supported between the walls of said container and having the intermediate portion of said string passing thereover, and said string having the other of its ends passed through 40 aligned openings formed in the bottom walls of said holder and said container. 45

75 2. An automatic toothbrush box, comprising a container with an open top, a cover hingedly mounted thereon for closing said top, a holder for toothbrushes and tooth paste tubes vertically slidably mounted in said container, a link connecting said holder and cover together for moving the cover open when the holder is lifted, and means for lifting said holder, comprising a string passing 55 through an aperture in said container to the exterior thereof and the inner end of said string being attached to said holder at a point to cause said holder to be lifted when the string is pulled, said string having one of its ends attached to the bottom wall of said container, a roller rotatively supported between the walls of said container and having the intermediate portion of said string passing thereover, and said string having the other of its ends passed through 60 aligned openings formed in the bottom walls of said holder and said container, said roller having its ends engaged through elongated slots formed in the walls of said holder and into openings formed in the walls of said container for rotatively supporting 65 70

75 75

said roller and for permitting said holder to move upwards within said container.

3. An automatic toothbrush box, comprising a container with an open top, a cover hingedly mounted thereon for closing said top, a holder for toothbrushes and tooth paste tubes vertically slidably mounted in said container, a link connecting said holder and cover together for moving the cover open when the holder is lifted, and means for lifting said holder, comprising a string passing through an aperture in said container to the exterior thereof and the inner end of said string being attached to said holder at a point to cause said holder to be lifted when the string is pulled, said aperture being arcuate, a lever pivotally mounted on said container, a clip for guiding said string mounted on said lever, and a clamp for closing said clip mounted on said container at one end of said arcuate shaped aperture.
- 20 4. An automatic toothbrush box, comprising a container with an open top, a cover hingedly

mounted thereon for closing said top, a holder for toothbrushes and tooth paste tubes vertically slidably mounted in said container, a link connecting said holder and cover together for moving the cover open when the holder is lifted, and means for lifting said holder, comprising a string passing through an aperture in said container to the exterior thereof and the inner end of said string being attached to said holder at a point to cause said holder to be lifted when the string is pulled, 5 said aperture being arcuate, a lever pivotally mounted on said container, a clip for guiding said string mounted on said lever, and a clamp for closing said clip mounted on said container at one end of said arcuate shaped aperture, a cotter pin 10 extending between the ends of said clip for maintaining said string in position therein, said clamp being formed with cutouts into which the ends of said cotter pin are adapted to extend when said 15 clip is engaged into said clamp.

ABRAHAM BRODY.
